UNITED STATES PATENT OFFICE.

CORNELIA A. HOPKINS, OF NEW YORK, N. Y.

DESIGN FOR A TOY FIGURE OR LIKE ARTICLE.

41,212.

Specification for Design.

Patented Mar. 7, 1911.

Application filed November 19, 1910. Serial No. 593,288. Term of patent 7 years.

To all whom it may concern:

Be it known that I, CORNELIA A. HOPKINS, a citizen of the United States, residing at New York, borough of Manhattan, in the county and State of New York, have invented a new, original, and ornamental Design for a Toy Figure or Like Article, of which the following is a specification, reference being had to the accompanying drawing, forming part thereof.

In the illustration, Figure 1 is a front elevation, and Fig. 2 is a side elevation showing my new design.

I claim:

The ornamental design for a toy figure or like article, as shown.

CORNELIA A. HOPKINS.

Witnesses:

WALTON HARRISON,
PHILIP D. ROLLHAUS.
